UNITED STATES PATENT OFFICE.

GUIDO TANZI, OF LONG ISLAND CITY, NEW YORK.

MACARONI DIE.

Application filed June 13, 1922. Serial No. 567,997.

To all whom it may concern:

Be it known that I, GUIDO TANZI, a subject of the King of Italy, and resident of Long Island City, county of Queens, State 5 of New York, have invented certain new and useful Improvements in Macaroni Dies, of which the following is the specification.

The device, the subject of this invention is a die for shaping macaroni and for producing in the shaped macaroni a spiral twist 10 or turn.

I have found that macaroni produced in strips, spirally wound has many advantages, in that it will cook more uniformly and will 15 not mass in cooking or serving, beside being more agreeable in appearance and more appetizing than flat or tubular macaroni.

Means have been employed in the past for twisting macaroni, but such means were 20 mechanical to an extent that the amount of twist could not be controlled and the macaroni was caused to pass through an additional rotating guide plate. This adds complication to the machine and makes the production of short lengths impossible. 25

In my device, the twist is imparted by the construction of the die and may be a single, double or quadruple spiral and the cross-sectional outline of the finished product may 30 have any one of a number of different shapes.

In the specification which follows, I will describe the construction of my die and the accompanying drawings should be referred to for a complete understanding of the specification which follows.

In the drawings:—

Fig. 1, is a plan view of a die.

Fig. 2, a side elevation, partly in section.

Fig. 3, a reverse plan view.

Fig. 4, an elevation and section of the material produced in the die shown in Figs. 1 and 3.

Fig. 5, a fractional, top plan view of a die of different construction.

Fig. 6, a reverse plan view of the part shown in Fig. 5.

Fig. 7, is an elevation and section of the material produced by the die shown in Figs. 5 and 6.

Fig. 8, is a fractional view of a die having four feeding apertures.

Fig. 9, is a reverse plan view of Fig. 8.

Fig. 10, is an elevation in section of the product shown in Figs. 8 and 9.

Fig. 11, is a view similar to Fig. 5.

Fig. 12, is a reverse plan view of the die shown in Fig. 11, and

Fig. 13, is an elevation and sectional view of the product of the die shown in Figs. 11 60 and 12.

Similar reference numerals indicate like parts in all the figures where they appear.

Because of the peculiar construction of my die, I prefer that it should be made in 65 two parts, an upper plate 15 and a lower plate or supporting member 16 and these members may be secured together by means of a screw 17 arranged at the mid center of the plates or in some other desirable manner. 70

In the upper plate 15, I produce a plurality of recesses as shown at 18 and 19. These recesses I may refer to as feeding orifices, as the dough mass moving downward under pressure of the piston, not shown, will be 75 received into these feeding orifices to be discharged from them through apertures in the sides of the orifices as shown at 20 and 21 and it will be noted that in the construction shown in Figs. 1 to 3 inclusive, the apertures 20 and 21 open toward each other.

To relieve the pressure which would accumulate in the flat bottomed recess and to promote the discharge therefrom, I form a projection 22 or 23 in the bottom of each receiving recess.

In the plate 16, I produce a plurality of discharge orifices as shown at 24 and 25 and as indicated in section at 26 in Fig. 2 and I call particular attention of the fact that the 90 apertures through each pair of receiving orifices enter and are connected with a single discharge orifice, that is each two receiving orifices feed one discharge orifice.

While the shape of the apertures 20 or 21 95 may be varied at will, I desire that pairs of apertures should be angularly disposed to each other, so that when the ribbon of dough is discharged through the aperture it will tend to rotate.

In discharging into the orifices 26, the ribbons of dough passing through the apertures 20 and 21 are brought together so that their edges touch and as the dough is plastic and adhesive the edges of the two projecting ribbons will adhere to each other and rotate together, thus producing a spiral as shown in Fig. 4.

In Fig. 5, three receiving orifices 27, 28 and 29 discharge into one discharge orifice 110

30. The spiral product 31 produced from the die, formed as shown will have three wings as shown in the sectional view at 32.
- 5 In Figs. 8 and 9, the four receiving orifices, 33, 34, 35 and 36 feed one discharge orifice 37. This product will be shaped as a spiral, but will have four wings as shown at 38. In the die shown in Figs. 11 and 12, I may place an ordinary pin member 39 in the discharge passage of the orifice 40; so that the product while turned in a spiral as shown at 41 will have a central hollow as indicated at 42 in Fig. 13. In this product we have all of the advantages of spirally turned and hollow macaroni and it will be understood that the forming pin may be provided in any other of the dies here shown and that dies of other shapes may be readily produced.
- 10 20 While other modifications may be made within the scope of the appended claims, I prefer the whole as shown and described.
- 15 Having carefully and fully described my invention what I claim and desire to obtain 25 is:—
- 30 1. A macaroni die comprising a plurality of plates secured together, one said plate being provided with a plurality of receiving orifices arranged in pairs and the other said plate being provided with a plurality of discharge orifices each discharge orifice communicating with a pair of receiving orifices and an irregularly shaped passage connecting each pair of receiving orifices with its 35 co-acting discharge orifices.
- 40 2. A macaroni die comprising a plurality of plates secured together, one said plate being provided with a plurality of dough receiving orifices arranged in pairs and the other said plate being provided with a plurality of discharge orifices each of which communicates with a pair of receiving orifices, the receiving orifices having apertures in their side walls said apertures being directed out of the radial line of said discharge orifices.
- 45 3. A macaroni die comprising a plurality of plates secured together, one said plate being provided with a plurality of receiving orifices arranged in pairs and the other said
- plate being provided with a plurality of discharge orifices each communicating with one pair of receiving orifices, each pair of receiving orifices being provided with discharge apertures in their nearest adjacent sides, said discharge apertures being directed out of the radial line of said discharge orifices, to impart a rotary motion to the material passing therethrough. 55
4. A macaroni die comprising a plurality of plates secured together, one said plate being provided with a plurality of receiving orifices arranged in pairs and the other said plate being provided with a plurality of discharge orifices each communicating with a pair of receiving orifices and projections in the bottom of said receiving orifices to direct the material passing. 60
5. A macaroni die comprising a plurality of plates secured together, one said plate being provided with a plurality of receiving orifices and the other said plate being provided with a plurality of discharge orifices, each said discharge orifice communicating with a plurality of receiving orifices and each said receiving orifice being provided with a discharge aperture in the wall thereof, all said discharge apertures of each associated group communicating with a single discharge passage, arranged in the nearest 65 adjacent side of the plate, wherein the receiving orifices are produced. 70
6. A macaroni die comprising a plurality of plates secured together, one said plate being provided with a plurality of receiving orifices arranged in pairs and the other said plate being provided with a plurality of discharge orifices each communicating with a plurality of receiving orifices, said receiving orifices being provided with discharge apertures in the side walls thereof, said apertures tending toward each other, though arranged at an angle to impart a 75 rotary motion to the material passing therethrough, a plurality of said discharge apertures communicating with each said discharge orifices. 80
- 85 Signed at the city, county and State of New York, this 19th day of May, 1922.
- 90 GUIDO TANZI.
